[57] ABSTRACT

This invention relates to an improvement in a vertical boiler for heating non-boiling heat-transfer liquids having two tightly wound axially symmetrically coiled pipe walls concentrically positioned at a distance with respect to each other inside an axially symmetrical housing, the external wall extending to the boiler bottom and radially delimiting the outside of a riser for flue gas, said riser surrounding the internal wall, aperture means in the upper end of said housing for the introduction of heating means, and a coiled pipe spiral constituting the boiler bottom, the improvement comprising an internal pipe wall which extends to the boiler bottom, at least said internal wall with the lowermost pipe winding being supported by the boiler bottom, and gaps between the lower coils of said internal pipe wall forming a connection between the space enclosed by said internal wall and said riser.

BOILER FOR HEATING NON-BOILING HEAT TRANSFER LIQUIDS

The present invention relates to a vertical boiler for heating non-boiling heat transfer liquids, particularly oils, with two tightly wound axially, or rotationally, symmetrical coiled or serpentine pipe side walls being concentrically disposed, one within the other, and at a distance with respect to each other, inside an axially symmetrical boiler housing. The internal wall radially delimits the central furnace, and the external wall extends to the boiler bottom and radially delimits toward the outside a riser enclosing the internal wall and therewith also the portion of the boiler through which flue gas flows. A feed line extends into the boiler through the upper end wall for an air-fuel mixture or for hot flue gas, and a coiled or serpentine pipe spiral constitutes the boiler bottom, which preferably drops downwardly toward the center.

Boilers of this particular type are known from Ger. Gebrauchsmuster No. 1,997,746.

While it is preferred, according to the present invention, that the coiled pipe walls as well as the boiler housing are constructed so as to be cylindrical, the configuration of the coiled pipe walls and that of the boiler housing in the prior art construction is conical. In the prior art construction, the internal coiled pipe wall terminates at a considerable distance from the boiler bottom, so that below this wall the initially downwardly flowing flue gases with turn around and be adapted to flow upwardly, in the space or chamber between the internal and the external walls in which a further coiled pipe arrangement is provided for, until they reach the stack of the boiler. Both in the present invention and also in the prior art construction, a burner, and preferably an oil burner, is disposed on top of the preferably removable lid or cover of the boiler.

In comparison with this prior art construction, the present invention provides for a boiler of the type outlined hereinabove in which the thermal load or charge of the pipes in the various coiled pipe walls can be determined very precisely, whereby the danger of local overheating of the coiled pipes, and thus of a harmful action of the heat carrier flowing into the heating tube coils is reduced to a minimum.

Further, in the boiler proposed by the present invention, the coiled pipe construction constitutes the supporting structural element of the boiler itself so that the boiler housing now serves merely for purposes of insulation. The combination of these advantageous features is rendered possible, according to the present invention, by virtue of the facts that the internal wall also extends to the boiler bottom; that at least the internal wall with the lowermost tube or pipe coil is supported by the boiler bottom, and that the connection between the furnace and the riser is established by the gaps in the lower portion of the internal wall being wound with a distance. Due to the fact that the deflection or return of the flue gases from the furnace into the riser is accomplished through gaps in the internal wall, and that these gaps also still are positioned in the lower area of the internal wall, practically the entire heat radiation of the flame burning in the furnace is absorbed from the internal wall, which latter may be correspondingly dimensioned. The external wall, or even several outwardly situated coiled pipe walls then must be dimensioned only in such a fashion that they will faultlessly

5 withstand the heat absorption by convection. As a consequence of the construction as described hereinabove it becomes possible, in turn, to cause the internal wall, which is as a rule the heaviest and strongest, to be seated directly upon the boiler bottom, so that the boiler bottom may be utilized as a supporting element for the internal wall, and preferably also the external wall.

10 Due to the subdivision of the coiled pipes leading the heat carrier into two strictly different or separate groups, one of which is heated by convection and radiation from the furnace, whereas the other one is heated merely by convection by the flue or boiler gases that have left the furnace, the thermal load of the coiled pipes and the flow velocity of the heat carrier therein may be calculated very accurately so that maximal heating is achieved without the danger of overheating.

20 The gaps between the various serpentine pipe coils or turns in the lower region of the internal wall extend advantageously approximately over the lower 20 percent of the total height of the internal wall.

25 Another advantage of the construction proposed by the present invention is that, by reason of the precise dimensioning of the gaps, the pressure drop inside the boiler, and therewith the weight rate of flow of the flue gas may be accurately dimensioned.

30 Due to the fact that the invention — as is generally known per se — delimits the space through which flue gas flows toward the outside by means of the external tightly-wound heating coil pipe wall, no uncooled surfaces practically will be present in the entire furnace, which increases the safety considerably. Since in the 35 external wall standing upright on the boiler bottom with a helically-extending lowermost turn or coil, such as is preferred, a gap remains free between the bottom and the lowermost coil or turn, it is preferred in this construction that the external wall encloses or surrounds the boiler bottom from the outside so that the lowermost coil does not extend over but next to the boiler bottom so that such a gap is eliminated.

40 In this manner acts also the boiler bottom construction used in the present invention which prevents the 45 heat storage in the otherwise customary bricked boiler bottoms. This is of particular significance in boilers serving for heating heat transfer liquids which do not boil, since heat carriers of this type are sensitive to overheating as a rule. When the circulating pump in a 50 heating system including such a heat carrier breaks down, it is quite possible that in boilers which are not constructed as proposed by the present invention, local overheating, and therewith possibly even the destruction of the entire boiler system, may be produced much 55 more easily.

60 In order to assure a flawless support of the internal wall by the boiler bottom, the lowermost coil or turn of the internal wall extends preferably in a helical manner so that it will rest on the one hand along a spiral line against the boiler bottom, and on the other hand also against the next higher and helically-extending coil or turn of the tube or pipe constituting the wall. In this manner, the lowermost coil carries the entire wall. In principle, it may extend in a spiral manner also toward the outside, but it is preferred that the lowermost coil or turn of the internal wall reduces its radius toward the end thereof being farther removed from the wall.

The gaps between the lower coils are advantageously retained true to size or dimension in each case only with spacer means being welded to one of the two tube or pipe coils delimiting the gap. This assures a maximal yielding of the entire construction with regard to thermal stresses, which in turn increases the service life and the carrying capacity of the boiler. The spacer means advantageously have approximately the shape of short rods which thicken again toward the two ends thereof.

The pipes constituting the walls preferably have a circular cross-section in the usual manner.

The lowermost coil of the internal wall may terminate in the boiler bottom either centrally downwardly, or on the outside. The latter arrangement is preferred since as a result an excessive exposure of the last end of the lower coil with respect to the flame is effectively prevented.

For purposes of improving the thermal efficiency, a third coiled pipe wall may be disposed between the two walls in the riser, which is preferably wound or coiled at a distance. This is known per se. But even further coiled pipe walls are possible. Moreover, additional fallers and risers may be disposed between the external wall and the internal wall. Preferred, however, is the construction as outlined at the beginning of this paragraph.

The coiled pipe walls are preferably radially held at a distance with respect to each other by means of axial rods, as is also known per se. But in contrast to the state of the art, the axial rods according to the present invention are preferably not welded to the coiled pipe walls, but are simply inserted between the latter. As a result, the axial rods may be exchanged with a minimum amount of expenditure. Another significant advantage of this construction is that no weakening of the coiled pipe walls is caused by welded joints with these spacer rods. This rod arrangement too is rendered possible only as a result of the strict separation between the radiating portion and the convection portion.

The welded joints between the various pipes constituting the coiled pipe walls are preferably so provided for that the welding seam projects neither outwardly nor inwardly. This facilitates not only the tight winding or coiling, but in addition thereto prevents inaccuracies in the flow of the heat carrier, and the formation of dead spaces which may, in turn, lead to harmful actions of the heat carrier.

The internal pipe wall is preferably connected at the top to the return connection of the boiler and at the bottom to the external wall which adjoins at the top the boiler flow or lead connection.

The arrangement just described above has the advantage that the most thermally stressed internal wall is passed through by the relatively cool heat carrier which has already given off its heat.

The third wall is preferably disposed parallel to the external wall.

The inventive provision of the boiler with a self-supporting heating coil system renders it possible — as is indeed preferred — that the uppermost coil of the internal wall carries the cover of the boiler. For this purpose, this coil extends likewise advantageously in a spiral fashion. In contrast to the lowermost coil, the spiral extends in this case, however, advantageously outside of the second highest helically-extending coil.

In order to assure a perfect closure of the cover during the thermal expansions of the heating coil walls and during the corresponding lifting and lowering of this cover, the latter is preferably equipped with a circumferential collar which is immersed into a groove being upwardly open and filled with a pourable or plastic sealing material, and which groove is positioned in turn at a sheet metal sleeve surrounding or enclosing the external pipe wall. The groove may be filled, for example, 5 with sand or slag.

The introduction of the lowermost coil of the internal wall into the boiler bottom is effected advantageously in a direction such that the end of the spiral channel in the bottom is rinsed by the liquid. This construction is 10 to be preferred whenever the boiler bottom is formed by two embossed sheets or plates between which extends a spirally provided web which constitutes the spiral channel for the heat carrier. Since it is not possible to connect, without a considerable technical expenditure, the lowermost coil of the internal wall in a flow-technically perfect manner to such a spiral channel, the formation of dead spaces can be avoided on the basis of the inventive teaching. For this purpose it is sufficient that the end of the pipe forming the lowermost 15 coil is allowed to further project a short distance at least on one side into the boiler bottom, and that this end has a curvature such that the flow is initially directed into the corner otherwise forming a dead space. It is equally possible to simply weld on a corresponding 20 reversing sheet or plate.

The lowermost coil of the external wall preferably extends in a helical manner and is supported, by means of supporting blocks being welded thereto, against the boiler bottom, or a flange surrounding the same. These 25 supporting blocks are preferably welded to the pipe forming the coil with considerably longer welding seams than to the boiler bottom or the flange. In case the welding seam breaks here due to thermal expansions, it will not break at the connecting point to the 30 pipe thereby endangering the boiler.

The lowermost coil of the internal wall, which carries the internal wall, is advantageously supported from the inside by means of a spirally-extending rod welded to the boiler bottom. Instead of a rod extending all 35 around, shorter rod pieces also may be welded to the boiler bottom and will secure the lowermost coil by contact from the inside. In principle, such supporting 40 rod pieces may be applied also on the outside.

In the boiler bottom used according to the present 45 invention it is essential that the flow perfectly follows the theoretical or desired spiral path. This was not always assured in the heretofore known constructions since the spirally-extending web between the two sheets or plates was welded only to one of the two sheets.

This difficulty is circumvented, according to the present 50 invention, in that the vertical sheet band spiral extending between the two sheets constituting the boiler bottom is butt-welded to one sheet, preferably the sheet facing the furnace, whereas the other edge thereof extends through a spiral slot of the other sheet and is welded with the latter from the outside.

The present invention will now be described herein- 55 after in further detail on the basis of and with reference to the schematic drawings which show the subject matter of the invention in a preferred embodiment thereof, and wherein

FIG. 1 is an axial view through a boiler according to the present invention,

FIG. 2 illustrates the boiler flow connection to the heating coil walls;

FIG. 3 illustrates the arrangement of a spacer means or member in the gap between two heating coils of the internal wall at an enlarged scale as compared to FIG. 1;

FIG. 4 is a perspective view of a spacer means or member at an enlarged scale as compared to FIG. 3;

FIG. 5 illustrates the cover seal of the boiler at an enlarged scale as compared to FIG. 1;

FIG. 6 illustrates the type of welding of a spiral web band into the two sheets or plates constituting the boiler bottom at an enlarged scale as compared to FIG. 1;

FIG. 7 illustrates the welding of a supporting rod on to a supporting coil of a boiler wall, and

FIG. 8 is a top plan view of the two lowermost coils of the internal heating coil wall.

The boiler proposed by the present invention and illustrated in the accompanying drawings is equipped with a supporting bottom ring 1 from steel from which upwardly extend, for example, four vertical web sheets or plates 2. Welded to the upper edges of these web plates — as is apparent from the drawings — is a ring 3 having an angle section and whose vertical web carries the boiler bottom 4. The boiler bottom 4 consists of two embossed sheets or plates 5 and 6 which are welded with the peripheral edges or rims thereof to the vertical web of the angle iron section 3. Disposed between the embossed plates 5 and 6 extending at a distance with respect to each other is a sheet band spiral 7 which forms in the boiler bottom, together with the two plates 5 and 6, a heating coil spiral passed through by the heat carrier. The sheet or plate band spiral 7 is welded with the upper rim thereof to the plate 5, as is more clearly apparent from FIG. 6, whereas the lower rim of this plate band spiral 7 extends through a spiral slot in the lower plate 6 and is tightly welded from the outside with the two edges of this slot, as is equally apparent from FIG. 6. As a result of this construction, the coiled pipe spiral formed by the boiler bottom is absolutely tight, and short-circuiting is not possible.

Seated upon the edge or rim of the boiler bottom is the internal coiled pipe wall 8. It is evident from the drawings that between the lowermost four, purely spirally extending coils of the coiled pipe wall 8 by winding the latter with interstices, gaps 9 have remained free through which the flue gases may enter from the furnace 10, being enclosed or surrounded by the coiled pipe wall 8, radially outwardly into the riser 11. In the zone or area above the lower four spiral windings of the wall 8, the latter is not so coiled or wound so that a radial issuance or discharge of flue gases and flame radiation toward the outside is not possible in this area.

Adjoining the lowermost helically-extending winding 12 of the wall 8 that has again been shown completely in a top plan view in FIG. 8, is a further spirally-extending winding 13 which, beginning from the connection thereof to the pipe 12, as indicated in FIG. 8 by a radius line, will constantly decrease its radius in a manner such that the winding 13 will, on the one hand, rest on the entire length thereof against the plate 5 of the boiler bottom and, on the other hand, carry the superimposed helically-extending pipe winding 12 also on the entire length thereof, along a line of contact. The

pipe winding 13 is welded at 14 to a correspondingly provided intake connection 15 in the boiler bottom. The intake connection 15 passes through the upper boiler bottom plate 5 with an oval opening. Its wall portion being disposed on top in FIG. 8 and behind the drawing plane in FIG. 1 projects — as is visible in FIG. 1 — into the outermost heating coil winding of the boiler bottom so that a downwardly-directed heat carrier flow in the coiled pipe wall 8 will initially be slightly reversed or deflected in the opposite direction so that it rinses the angles existing there at the beginning of the heating coil spiral in the boiler bottom.

In order to hold the lowermost winding 13 securely on the boiler bottom, to which it is incidentally not further welded, short round steel rod pieces 16 are so welded to the boiler bottom at a distance with respect to each other that they will lie precisely flush along a line of contact against the coiled pipe winding 13. As a result, it is secured against a lateral displacement due to the influence of thermal expansions. It carries the entire weight of the internal coiled pipe wall 8. In order that the latter not be compressed due to its own weight and close the gaps 9, spacer means or members 17 are inserted into the gaps 9 whose preferred specific shape is apparent from FIGS. 3 and 4. The spacer members 17 are welded in each case only to one of the two windings 18 and 19 being held at a distance by them, or are simply inserted. By virtue of the concave configuration or curvature of their central portion they not only maintain the correct distance or spacing; they constitute at the same time a radial guide for the pipes being separate therefrom. When the spacer members are provided with nose portions extending to the next pipe wall, these nose portions may replace the aforesaid spacer members at least partly.

At the upper end the return connection 20 adjoins the internal pipe wall 8.

Provided adjoining the uppermost helically-extending winding of the internal pipe wall 8 is a further spirally-extending winding 21 which terminates in the connection 20. The uppermost winding 21 extends in a manner such that, on the one hand, it rests on its entire length along one line against the upper winding of wall 8 extending along a helical line and, on the other hand, along a spiral line extending in a plane at the boiler cover 22. In this manner, the uppermost winding of the innermost wall 8 carries the cover 22 of the boiler, which is adapted to be lifted and lowered with the thermal expansions of this winding. In the center, the cover 22 has an aperture 23 for the insertion of, for example, an oil burner. For purposes of sealing with respect to the boiler housing 24 which essentially consists of two coaxial sheet or plate jackets 25 and 26, having the extension apparent from the drawings and whose interstices are filled with a suitable insulating material, such as, for example, a glass wool, the cover 22 is surrounded by a downwardly open U-shaped, or T-shaped, or angle section rod 27 bent to form a ring. The outer leg of the ring 27 thus formed is immersed into the interior of an upwardly open U-shaped section ring 29 which is secured in a suitable manner to the top of the boiler housing 24. The arrangement is so made that within the thermal expansions to be expected, the outer leg of the U-shaped section ring 27 will not reach the bottom of the outer U-shaped section ring 29. For purposes of a perfect sealing, sand 31, for example, is placed in the outer U-shaped section ring 29.

It is apparent from the foregoing description that the internal coiled pipe wall 8 constitutes a unit in a self-supporting construction with the internal boiler bottom 4 which rests by way of the web plates 3 on or against the supporting ring 1. Nevertheless, a maximum movability of the windings of the internal wall 8 with respect to each other is assured.

From below, there adjoins the center of the heating coil spiral formed by the boiler bottom an approximately radially extending pipe line 30 for the heat carrier liquid which at the end is connected to the external coiled pipe wall 32. This external pipe wall is also tightly coiled or wound, like the upper part of the internal wall 8, so that the flue gases flowing upwardly between the internal wall and the external wall in the rise will not come into contact with the internal plate 26 of the boiler housing.

From the description contained hereinabove it is apparent that in the internal boiler area which comes into contact with the flue gases, there are no parts not cooled by heat carrier liquid which could constitute heat containers or reservoirs of such size or extent that the heat stored therein, in case of a breakdown of the circulation of the heat carrier, could pass over onto the heat carrier now standing still and adversely affect the latter.

In the external coiled pipe wall 32, the heat carrier liquid, which flows helically downwardly in the internal wall, flows helically upwardly. From the uppermost winding of the wall 32, a short pipe connection 33 projects upwardly and in turn passes over into the discharge connection 34 of the boiler. The discharge connection preferably extends parallel to the return connection 20 at the same height in FIG. 1, slightly ahead of the drawing plane.

In the embodiment shown, which is also preferred, there are disposed between the internal coiled pipe wall 8 and the external coiled pipe wall 32 at least one and preferably a further central coiled pipe wall 35 being passed through parallel to the external coiled pipe wall 32, and whose various windings extend on the entire height of this wall at a distance with respect to each other so that these pipes are circumcirculated particularly well by the flue gas stream. It is also possible to provide spacer means or members of the type of the spacer members 17 between the pipes of this wall. These spacer members are likewise advantageously firmly welded to one of the two pipe windings being maintained at a distance by them. At the lower end, the lowermost winding of the intermediate wall 35 also connects to the line 30. The upper end of the wall 35 is also connected to the discharge connection 34, as is apparent from the drawing.

While in smaller boilers the internal wall 8 and the external walls are preferably constructed in a single-threaded manner, the external wall 32, the central wall 35 and also the internal wall in larger boilers are preferably constructed in multiple-thread.

Also the external wall 32 and the central wall 35 rest in a self-supporting manner on the horizontal flange of the angle section ring 3, as is evident particularly from FIG. 1. Since also the lowermost winding of these two walls in the embodiment shown rises upwardly in a helical fashion without a spiral supporting winding, round steel pieces 40, as shown in FIG. 7, are welded at a distance to the respectively lowermost winding 41. The round steel pieces 40 are in this case preferably welded

with two relatively long welding seams to the pipe winding 41, and only with a small short welding seam to the horizontal leg of the angle section ring 3. If damage arises here due to thermal expansion or other forces, it may result merely in a break of the welding seam between the round steel piece 40 and the leg 3, but cannot produce a break of the welding seams between the round steel piece 40 and the pipe 41.

The round steel pieces 40 are placed so closely from within or from without or even from both sides against the corresponding pipe winding 41, in each case prior to the welding operation, that it will be perfectly carried. This means that already prior to welding, the round steel piece 40 should in each case rest along a line of contact against the horizontal leg of the angle section 3 and also against the pipe section 41 along a line of contact.

In order to fix or secure the three coiled pipe walls also in the radial direction, rods 45 from a difficulty oxidizable grade of steel are inserted between the internal pipe wall and the central pipe wall radially and at a distance with respect to each other. These rods are preferably connected at the upper ends thereof — as is apparent from FIG. 1 — with further spacer rods 46 by means of welding with the aid of a short web piece, and these spacer members 46 maintain the central wall 35 and the external wall 32 at a distance. In the embodiment shown, the external rods 46 have circular indentations with which they keep the various pipes of the central wall 35 at a distance from each other. There is no need for using both of the possibilities shown for maintaining a spacing of the various windings of the central wall 35. Either spacer members or the notches in the external spacer rods 46 can be used for this purpose. If spacer members are present, preferably round steel rods or other rods are inserted as spacer rods, having a section which will not tilt even during tension between the walls, i.e., for example a square profile, or an equilateral triangular profile, or a flat profile whose largest extension extends in the circumferential direction.

When the spacer rods 45 and 46 must be exchanged, it is sufficient to separate the bridge connecting them at the upper end thereof. At that time, the rods 45 may be readily pulled out upwardly. The rods 46 have a flat iron profile and at the narrow edge or rim thereof the circularly bent indentations must be so turned prior to being pulled out that the circular-shaped notches will be freed from the pipes of the wall 35. Then they too may be pulled out upwardly and replaced by other rods. The heat capacity of these spacer rods 45 and 46 is so low that even in case of a breakdown of the circulating pump a harmful influence or action of the heat carrier inside the pipe coils by the heat being stored in the rods will be avoided with certainty.

In the embodiment shown, the hot flue gas generated in the furnace or introduced into the latter from above flows initially downwardly in the furnace 10 where it heats the internal wall 8 and the boiler bottom by convection and radiation. Thereafter, the flue gas flows through the gaps 9 radially outwardly into the area between the wall 8 and the wall 32, where — equally circumcirculating the central wall 35 — it flows upwardly, so as to leave the boiler through the stack 50.

In the embodiment shown, dead spaces at the beginning and end of the bottom spiral are avoided by corresponding deflecting arrangements; instead it also would

be possible to provide there apertures in the wall to the next-following or preceding winding of the spiral. These apertures must be so small that the short-circuiting effect caused thereby will affect only a small part of the flow.

It will be obvious to those skilled in the art that many modifications may be made within the scope of the present invention without departing from the spirit thereof, and the invention includes all such modifications.

What is claimed is:

1. In a vertical boiler for heating non-boiling heat-transfer liquids having two tightly wound axially symmetrically coiled pipe walls concentrically positioned at a distance with respect to each other inside an axially symmetrical housing, the external wall extending to the boiler bottom and radially delimiting the outside of a riser for the flue gas, said riser surrounding the internal wall, aperture means in the upper end of said housing for the introduction of heating means, and a coiled pipe spiral constituting the boiler bottom,

the improvement comprising an internal pipe wall which extends to the boiler bottom, at least said internal wall with the lowermost pipe winding being supported by the boiler bottom and said lowermost winding of the internal wall extending spirally in a manner such that it rests on the one hand along a spiral line against the boiler bottom and, on the other hand, also against the next-higher helically-extending winding of the pipe constituting the wall, and gaps between the lower coils of said internal pipe wall forming a connection between the space enclosed by said internal wall and said riser.

2. A boiler according to claim 1 in which the lowermost winding of the internal wall decreases its radius toward the wall-removed end thereof.

3. A boiler according to claim 1 including spacer means for maintaining the gaps between the lower coils true to size.

4. A boiler according to claim 1 in which the lowermost winding of the internal wall terminates into the boiler bottom from above.

5. A boiler according to claim 5 in which the introduction of the lowermost winding of the internal wall into the boiler bottom is effected in a direction such that the end of a spiral channel in the bottom is rinsed

by the liquid.

6. A boiler according to claim 1 in which the lowermost winding of the internal wall terminates into the boiler bottom at the outside.

5 7. A boiler according to claim 1 including a third coiled pipe wall in the riser, the coils of said wall being wound at a distance from each other.

8. A boiler according to claim 8 including means whereby the third wall is maintained parallel to the external wall.

10 9. A boiler according to claim 1 including axial rods maintaining the coiled pipe walls at a distance with respect to each other.

15 10. A boiler according to claim 10 in which the axial rods are connected with the pipe walls by frictional contact.

11. A boiler according to claim 10 in which the axial rods are connected with the pipe walls by form-locking contact.

20 12. A boiler according to claim 1 in which the internal pipe wall is connected at the top to a return connection of the boiler and at the bottom to the external wall, which latter connects to the boiler discharge connection at the top of said external wall.

13. A boiler according to claim 1 in which the uppermost winding of the internal wall carries a cover of the boiler and for this purpose extends spirally.

14. A boiler according to claim 13 in which said cover is immersed with a circumferential collar into an upwardly open groove filled with a sealing material, said groove being positioned at a sleeve surrounding the external pipe wall.

15. A boiler according to claim 1 in which the lowermost winding of the external wall extends helically and is supported by means of supporting blocks welded thereto on the boiler bottom.

16. A boiler according to claim 1 in which the boiler bottom consists of two plates between which extends a vertical metal band spiral which is butt-welded to one sheet whereas the other edge thereof projects through a spiral slot of the other sheet and is welded thereto from the outside.

17. A boiler according to claim 1 in which the external wall surrounds the boiler bottom from the outside.
